ROTARY AUTOMATIC LATCH TRIP SOCKET

Julius S. Beck, Los Angeles, Calif.

Application May 25, 1935, Serial No. 23,398

3 Claims. (Cl. 294—102)

This invention relates to fishing tools for removing a "fish", such as a drill pipe or tubing from wells, and more particularly to an automatic latch trip socket for gripping the drill pipe or tubing on the outside thereof and pulling the same from a well.

In the use of the conventional socket in well-fishing operations, it is necessary to rotate the socket in order to release it from the "fish". This is not possible in many operations when the socket grips the fish with considerable force, and consequently in applying great force to rotate the drill stem and socket, in order to release the socket from the "fish" the slips are often twisted out of shape and broken, and also the drill stem is often twisted and broken immediately above the socket, and the socket has to be left on the "fish", plugging the well hole, which may necessitate abandonment of the well, with the resulting loss of the well, casing and tools, or require other expensive fishing operations to remove the tools left in the well hole.

The general object of my invention is to provide an improved socket for use in well fishing operations, which may be readily released from the "fish" without rotating the socket.

A more particular object is to provide a socket of the character stated, which may be readily released from the "fish" by jarring the drill stem and socket slightly downwardly.

A further object is to provide a socket which may be readily released from the "fish" without rotating the socket when the "fish" is recovered.

Other objects and advantages will appear as this specification progresses, and the invention will be readily understood from the disclosure herein by those skilled in the art.

The invention is illustrated in the annexed drawing, which forms a part of this specification, and in which,

Fig. 1 is a view partly in elevation and partly in vertical longitudinal section, of my socket, shown with its slips expanded, for slipping the socket over the upper end of a drill pipe or tubing for enabling said slips to grip the outside thereof.

Fig. 2 is a view like Fig. 1, except that the socket slips are shown contracted into gripping engagement with the "fish".

Fig. 3 is a cross section of my socket taken on line 3—3 of Fig. 2.

Fig. 4 is a cross section of my socket taken on line 4—4 of Fig. 2.

Referring more particularly to the drawing in which corresponding parts are designated by the same reference characters in all the figures of the

drawing, my socket includes a socket shell 1; a socket head fitting 2 on the upper end of said shell; a socket centering guide 3 on the lower end of said shell; an annular packing 4 and packing ring 5 within said shell; slip-engaging surface 6 on the inside of said shell; slips 7; a spring cage 8; a slip-and-cage spring plunger 9; and a latch 10.

The shell 1 is provided with an internal thread 11 in its upper end for engagement with an external thread 12 on the lower end of the head fitting 2, and said head fitting is formed with an annular external shoulder 13 at the upper end of its thread 12 for engagement with the upper edge of said shell, whereby the lower end of said head fitting is tightly screw-seated in the upper end of said shell. The upper end of the head fitting 2 is formed with a conventional "box" 14 for engagement with the conventional "pin" on the lower end of a drill stem (not shown), whereby my socket is screw-seated on the lower end of said drill stem. The head fitting 2 is formed with a plunger bore 15 extending upwardly from its lower end to an upper end wall 16 in which bore the plunger 9 is slidably fitted, and the head fitting is provided with a smaller bore 17 extending from the bore 15 into the lower end of the "box" 14, in which smaller bore the upper end of a tube 18 is screw-seated, as at 19, which tube extends downwardly through the plunger bore 15 into the plunger 9 for the circulation of water through the socket.

A coil spring 20 is positioned in the plunger bore 15, surrounding the water-circulation tube 18, with one end of said spring bearing against the upper end wall 16 of the plunger bore 15 and the lower end of said spring bearing against the upper end of the slip-and-cage plunger 9, which spring 20 urges said plunger, cage 8 and slips 7 downwardly in the socket.

The slip-engaging surface 6 is formed on the inside of the shell 1 near the lower end of the casing and is of inverted internal conical formation for engaging corresponding external conical surfaces 21 on the slips 7, for contracting the slips when the slips move downwardly in the shell, and for allowing the slips to expand when the shell moves downwardly with relation to the slips.

The lower end of the shell 1 is provided with an internal thread 22 for engaging an external thread 23 on the upper end of the socket-centering guide 3, and said guide is formed with an external annular shoulder 24 at the lower end of its external thread 23 for engagement with the lower

edge of the shell 1, whereby said guide is screw-seated tightly in the lower end of said shell.

The packing 4 and the packing ring 5 are positioned in the casing 1 between an annular undercut shoulder 25, under the lower end of the slip-engaging surface 6, and the upper end 24' of the centering guide 3, the lower edge 26 of the packing ring resting against the upper edge 24' of said guide; and the lower edge 27 and upper edge 28 of the packing 4 resting respectively against the upper edge 29 of said packing ring and said shoulder 25, whereby said packing is compressed by the screw seated guide 3 between said packing ring and shoulder 25. The upper inner edge 4' of the packing 4 is converged to a smaller diameter than the remaining internal diameter of the packing, so as to lap the drill stem or tubing closely and form a seal therebetween, under the pressure of the downwardly circulating fluid, in order to direct the circulation of water or oil through the "fish" to loosen the same.

The slips 7 are swivelly and detachably connected to the plunger 9, to slide upwardly or downwardly in the shell, by inturned flanges 30, formed on the upper end of upstanding slip shanks 31, and an annular external groove 32, in the lower end of said plunger, into which groove extend said slip-shank flanges 30, so that the slips may be slidably moved outwardly for expansion thereof or inwardly for contraction thereof, and may turn relatively to said plunger. The slips 7 are formed with internal wickers 33.

The cage 8 comprises a band ring 34 and a plurality of vertically-disposed inwardly-bowed flat springs 35, secured at their lower ends to the inside of said band ring and at their upper ends to the inner side of an annular skirt 36 depending from the lower end of the plunger 9, said band ring and said skirt being located inside of the slip shanks 31.

The latch 10 comprises a vertically-disposed latch trigger 37, pivoted at its lower end, at 38, to the lower end of the head fitting 2, in a slot 39 therein, and an external undercut screw-thread 40 formed on the upper portion of the plunger 9, which thread is engaged by the upper engaging end 41 of said trigger, there being a leaf spring 42 secured to said trigger and pressing against the shell 1 for yieldably holding said end of said trigger in engagement with said screw thread.

The operation, uses and advantages of my invention are as follows:

The upper end of my socket being connected to the lower end of a drill stem by means of a "pin-and-box" joint, of which the box 14 forms one member, the plunger 9, cage 8 and slips 7, being in their uppermost position against the tension of the plunger spring 20 bearing upon the plunger 9, and held in such position by the engagement of the trigger 37 with the lowermost shoulder of the thread 40, and the slips being expanded with the conical slip surfaces 21 riding the upper portion of the conical shell surface 6, as shown in Fig. 1 of the drawing, my socket is lowered in a well hole over the upper end of a drill pipe or tubing 43, the inwardly-beveled lower curved edge of the socket guide 3 engaging the upper edge of said drill pipe or tubing and guiding the upper end thereof into the socket through its lower end, until the upper end of the drill pipe or tubing contacts the lower end of the plunger 9 and is positioned within the cage 8, with the cage flat springs 35 frictionally engaging the outside of said drill pipe or tubing and hold-

ing the slips against rotation, as shown in Fig. 1 of the drawing. The drill stem is then rotated, which rotates the head fitting 2, trigger 37, shell 1 and guide 3, while the cage 8, plunger 9 and slips 7 are held against rotation by the engagement of the cage springs 35 with the outside of the drill pipe or tubing, during which operation the upper end of the trigger 37, engaging the latch thread 40 and following said thread upwardly allows the spring 20 to expand and force 10 the plunger 9, cage 8 and slips 7 downwardly within the shell 1, whereupon the engagement of said spring 20, with the conical slip engaging surface 6 of the shell 1, forces the slips 7 inwardly or contracts the slips into gripping engagement, with the outside of the drill pipe or tubing as shown in Fig. 2 with such force that my socket cannot be pulled off said drill pipe or tubing while so gripped by my socket. The drill stem is then 20 pulled upwardly, and if the casing is not held in the well hole with too great resistance to the power applied to the drill stem, the drill pipe or tubing will be pulled out of the well hole by my socket. If the drill pipe or tubing is held in the 25 well hole with such resistance that it cannot be pulled by my socket by the power applied to the drill stem, a slight downward jar is applied to the drill stem, whereupon the latch trigger 37 escapes the latch thread 40 downwardly, while the slip- 30 engaging surface 6, of the shell 1, moves away from the slip-coating surfaces 21 and allows the slips 7 to expand out of gripping engagement with the drill pipe or tubing, thus releasing the socket from the drill pipe or tubing, in which released position the slips are held by the engagement of the latch trigger 37 with the lowermost shoulder of the latch thread 40, as shown in Fig. 1 of the drawing. My socket may then be pulled off the drill pipe or tubing and out of the well 40 hole, so that another fishing operation may be performed to recover the "fish".

When a drill pipe or tubing or a section thereof is recovered by my socket, my socket may be readily released therefrom by giving the socket a 45 slight downward jar, so that the latch trigger 37 will escape the latch thread 40 and allow the shell 1 and its latch-engaging surface 6 to move downward with relation to the slip-coating surfaces 21, whereupon the slips 7 will expand out of 50 gripping engagement with the drill pipe or tubing.

I claim as my invention:

1. In a socket as disclosed, a socket shell, a spring cage rotatably and slidably mounted in 55 said shell for frictionally engaging the drill pipe or tubing, slips mounted in said shell to be contracted into gripping contact with the drill pipe or tubing when the cage is moved in one direction with relation to said shell, and to be expanded, to 60 release the drill pipe or tubing when the shell is moved in said direction with relation to said cage, and means for moving the cage in one direction with relation to the shell upon rotation of said shell for enabling the slips to be contracted to grip the drill pipe or tubing, and for enabling the shell to be moved in said direction with relation to the cage without rotating the shell, for expanding the slips to release freely the drill pipe or tubing so that the socket may be lifted 65 freely off said drill pipe.

2. In a socket as disclosed, a socket shell, a head member on the upper end of said shell, a plunger slidably and turnably mounted in said head member, a plunger spring in said head 75

member, bearing at one end against the upper end wall of said head member and at its other end against the upper end of said plunger, a spring cage mounted on said plunger for frictionally engaging a drill pipe or tubing, slips mounted on said plunger to be contracted or expanded, interengaging inclined surfaces on said slips and said shell respectively to cause contraction and expansion of said slips when said shell is moved in one direction or the other with relation to said slips, and means for enabling said plunger and said slips to move downwardly with relation to said head and shell under the influence of said plunger spring, when said head is rotated, to cause said interengaging inclined surfaces to contract said slips into gripping engagement with said drill pipe or tubing, and for enabling said plunger and said slips to move upwardly with relation to said head and shell, against the tension of said plunger spring, without rotating said head and shell, to cause relative movement of said interengaging inclined surfaces to allow said slips to expand and release said drill pipe or tubing and to lock automatically said plunger and said slips against direct downward movement relative to said head and shell, with said slips released from said drill pipe or casing.

3. In a socket as disclosed, a socket shell, a head member on the upper end of said shell, a plunger slidably and turnably mounted in said head member, a plunger spring in said head member, bearing at one end against the upper end wall of said head member and at its other end against the upper end of said plunger, a spring cage mounted on said plunger for frictionally engaging a drill pipe or tubing, slips mounted on said plunger to be contracted or expanded, interengaging inclined surfaces on said slips and said shell respectively to cause contraction and expansion of said slips when said shell is moved in one direction or the other with relation to said slips, and a latch comprising a screw-thread on said plunger and a latch-trigger in said head, said trigger being constructed and arranged to engage said thread, when said head is rotated, for allowing said plunger and said slips to move downwardly, under the influence of said plunger spring, to cause said interengaging inclined surfaces to contract said slips into gripping engagement with the drill stem or tubing, and said trigger being constructed and arranged to escape said thread, to enable said plunger and slips to move upwardly, with relation to said head and shell, against the tension of said plunger spring, without rotating said head, to cause relative movement of said interengaging inclined surfaces, to allow said slips to expand and release said drill pipe or tubing.
